COMBINED TOASTER COVER AND TOAST RACK

Frederick W. Perl, Mansfield, Ohio, assignor to Westinghouse Electric Corporation, a corporation of Pennsylvania

Filed Nov. 10, 1961, Ser. No. 67,471

Term of patent 14 years

(Cl. D44—29)

FIG. 1 is a perspective view of a combined toaster cover and toast rack showing my new design, in toaster covering position;

FIG. 2 is a perspective view thereof in toast holding position;

FIG. 3 is a top plan view of the article shown in FIG. 2; and

FIG. 4 is a side elevational view of the article as shown in FIG. 2.

The toaster and slice of toast shown by broken lines in FIGS. 1 and 2 respectively are for illustrative purposes only.

I claim:

The ornamental design for a combined toaster cover and toast rack, substantially as shown and described.
